ABRAHAM TRAGER, OF NEW YORK, N. Y.

Letters Patent No. 65,986, dated June 18, 1867.

IMPROVEMENT IN HOOP-SKIRTS.

The Schedule referred to in these Letters Patent and making part of the same.

TO ALL WHOM IT MAY CONCERN:

Be it known that I, ABRAHAM TRAGER, of No. 20 Pike street, New York city, and State of New York, have invented an improved Ribbed or Corrugated Wire for Hoop-Skirts; and I do hereby declare the following to be an exact description thereof, reference being had to the accompanying drawings, and to the letters of reference marked thereon, making a part of this specification.

The nature of my invention consists in the use of ribbed or corrugated wires that can be used for hoop-skirts without or with any kind of coating or covering; and the object is to cheapen the price of hoop-skirts, and dispense with the expense of covering the wires with the usual covering of cotton, yarn, and other fabrics, and make the skirt more elastic, durable, and lasting.

A A represent the ribbed or corrugated wires of the hoop-skirt, that may be attached by tape, loops, spangles, or other clasps, as commonly manufactured.

The advantage of the ribbed or corrugated wires is, that they will not slip so easily through the clasps.

What I claim as my invention, and desire to secure by Letters Patent, is—

The use of ribbed or corrugated wires for hoop-skirts, either with or without any kind of covering, as herein described.

ABRAHAM TRAGER.
